(57) **CLAIM**

The ornamental design of a decorative edging and stepping block, as shown and described.

DESCRIPTION

FIG. 1 is a perspective view of a first embodiment of the decorative edging and stepping block showing the new design, with an upper surface having raised mounds that form a pattern;

FIG. 2 is a top view of the edging and stepping block of FIG. 1;

FIG. 3 is a front-side view of the edging and stepping block of FIG. 1;

FIG. 4 is a side view of the edging and stepping block of FIG. 1;

FIG. 5 is a rear-side view of the edging and stepping block of FIG. 1; and

FIG. 6 is a bottom view of the edging and stepping block of FIG. 1.

FIG. 7 is a perspective view of a second embodiment of the decorative edging and stepping block showing the new design, with the upper surface having recessed grooves that form the pattern;

FIG. 8 is a top view of the edging and stepping block of FIG. 7;

FIG. 9 is a front-side view of the edging and stepping block of FIG. 7;

FIG. 10 is a side view of the edging and stepping block of FIG. 7;

FIG. 11 is a rear-side view of the edging and stepping block of FIG. 7; and,

FIG. 12 is a bottom view of the edging and stepping block of FIG. 7.

FIG. 13 is a perspective view of a third embodiment of the decorative edging and stepping block showing the new design, with the upper surface having score lines that form the pattern; and,

FIG. 14 is a top view of the edging and stepping block of FIG. 13.

The front, left, right, rear and bottom sides of the third embodiment are the same as those shown in FIGS. 9-12 of the second embodiment.

The broken lines shown in FIGS. 1, 3-5, 7, 9-11 and 13 are for illustrative purposes only and form no part of the claimed design. The side views opposite those shown in FIG. 4 and FIG. 10 are mirror images, respectively.
